UNITED STATES PATENT OFFICE.

PETER M. HEINZ, OF DUBUQUE, IOWA.

WRENCH.

Application filed October 11, 1927. Serial No. 225,556.

This invention relates to wrenches, an object of the invention being to provide a wrench in which the movable jaw may be easily adjusted relative to the fixed jaw and then secured against movement so as to insure a perfect operation of the wrench.

A further object is to provide a wrench having improved construction and shape of fixed and movable jaws, improved mounting therefor, and improved operating means therefor.

With these and other objects in view, the invention consists in certain novel features of construction and combinations and arrangements of parts which will be more fully hereinafter described and pointed out in the claims.

In the accompanying drawings—

Figure 1 is a view in elevation of my improved wrench;

Figure 2 is a view, mainly in longitudinal section, of the wrench, a portion of the wrench being shown in elevation;

Figure 3 is a view in side elevation of a portion of the wrench taken at right angles to Figure 1;

Figure 4 is a view in elevation of a portion of a wrench, looking at the rear of the wrench shown in Figure 1;

Figure 5 is a view in transverse section on the line 5—5 of Figure 1.

Figure 6 is a view in transverse section on the line 6—6 of Figure 1.

1 represents the fixed jaw of my improved wrench, which is made integral with a shank 2. This shank 2 adjacent the operative end of the jaw is made angular, as shown at 3, and on the face of this angular portion a web 4' is formed. The major portion of the shank is screw-threaded, as clearly shown.

4 represents my improved movable jaw which has an angular opening 5 receiving the angular portion 3 of shank 2. In other words, this jaw is made with an angular portion 5 so as to receive the shank and move thereon, and is also made with a longitudinal groove 6 to receive the web 4' and insure a longitudinal sliding engagement and a rigid holding means against independent lateral movement of the jaws. The web 4' and the groove 6 are of such shape as to key the parts together, as shown in Figure 6.

The jaw 4 is recessed, as shown at 7 to accommodate a thumb nut 8 having screw threaded engagement with the shank 2, so that by turning this nut 8 the movable jaw may be adjusted relative to the fixture.

9 represents a handle which is of cylindrical form externally and has internal screw threads 11 at a plurality of points within the handle for engagement with the shank 2, and I may provide a set screw 12 in this handle to engage the threads of the shank to lock the handle against movement after adjustment.

A spacing sleeve 13 is positioned around the shank 2 between the movable jaw 4 and the handle 9, as clearly shown.

I would call particular attention to the shape of the fixed and movable jaws where they engage a nut bolt or other device. The fixed jaw has a somewhat egg-shaped opening 14 therein, and has an extension 15 on one face which is opposed to the operating member 16 of the movable jaw 4.

These parts 15 and 16 are of angular form internally, or in other words, their opposing faces are cut on an angle so as to properly engage a nut or bolt head, and by reason of the general egg-shape of the opening 14 a nut on a shaft may be readily removed, the opening 14 accommodating the shaft or bolt whether said shaft or bolt be central of the opening or at a position beyond the center.

I have illustrated in dotted lines in Figure 2, the position of the nut and bolt in the wrench so that it will be observed that the wrench can be positioned on the nut regardless of the length of the bolt and can be conveniently operated to remove the nut.

The inner or operating face of the movable jaw 4 is provided with a groove 17 there-in which may accommodate the key on a shaft or bolt and may function to engage any part of a device to be held or removed.

The operation is as follows:

The thumb nut 8 is turned to position the movable jaw as may be desired, and then the handle 9 is turned to clamp the parts against movement and, if the wrench is to be opened the handle part 9 must of course first be unscrewed a certain distance and then the movable jaw can be adjusted to the position desired.

While I have illustrated what I believe to be a preferred embodiment of my invention it is obvious various changes and alterations might be made in the general form of the parts described without departing from the invention and hence I do not limit myself to the precise details set forth but consider myself at liberty to make such changes and alterations as fairly fall within the spirit and scope of the appended claims.

I claim:

1. A wrench of the character described, including a fixed jaw, a screw threaded stem on the jaw having an angular portion, a web 5 on the angular portion of the stem, a movable jaw having a recess receiving the angular stem and keyed to the web and having a lateral recess therein, a thumb nut in the lateral recess and on the thread of the stem 10 for moving the movable jaw, a handle having screw threaded engagement with the stem, and a spacing sleeve between the handle and the movable jaw.

2. A wrench of the character described, 15 comprising a fixed jaw, a stem secured to the fixed jaw and a movable jaw mounted to slide on the stem, one of said jaws having an opening therein of general egg-shape, and an extension projecting from the jaw having the 20 opening therein, said extension and the other jaw having opposed angular faces.

3. A wrench of the character described, comprising a fixed jaw a stem secured to the fixed jaw and a movable jaw mounted to slide 25 on the stem, one of said jaws having an open-

ing therein of general egg-shape adapted to receive a shaft therein, and an extension projecting from the jaw having the opening therein, said extension and the other jaw having opposed angular faces, one of said angular faces having a shaft key receiving groove therein. 30

4. A wrench of the character described, including a fixed jaw, a screw threaded stem on the jaw having an angular portion, a web 35 on the angular portion of the stem, a movable jaw having a recess receiving the angular stem and fit over the web and having a lateral recess therein, a thumb nut in the lateral recess and on the thread of the stem for 40 moving the movable jaw, a handle having screw threaded engagement with the stem, a spacing sleeve between the handle and the movable jaw, and a screw in the handle adapted to engage the threads of the stem. 45

Signed at Dubuque in the county of Dubuque and State of Iowa this first day of October, A. D. 1927.

PETER M. HEINZ.
